UNITED STATES PATENT OFFICE.

WILLIAM JAMES TRAXEL, OF CHICAGO, ILLINOIS.

SAFETY DEVICE FOR GAS DRUMS.

Application filed November 11, 1920. Serial No. 423,261.

To all whom it may concern:

Be it known that I, WILLIAM JAMES TRAXEL, a citizen of the United States, residing at Chicago, county of Cook, and 5 State of Illinois, have invented certain new and useful Improvements in Safety Devices for Gas Drums, of which the following is a specification.

The gas drums with which this invention 10 is particularly concerned are ordinarily heavy steel tubes completely closed at one end and closed at the other end except that provision is made for the introduction and exhaustion of the compressed gas. These 15 drums are ordinarily used for storage and transportation of compressed gases such as oxygen and hydrogen. The gases are commonly forced into the drums by a pump under very high pressure until the drums 20 are fully charged. It not infrequently happens that such drums when charged with gas are exposed to temperatures which raise the pressure above the safety point, and where no precautions have been taken to the 25 contrary explosions have occurred which endanger the lives of the operators and the property adjacent the exploded drum. It is common practice, therefore, to provide means for releasing the gas when the pressure 30 is exceeded, and the device most generally used for this purpose is a metal disk interposed in the connection between the interior of the drum and an outlet to the atmosphere, 35 the disk being of such strength as to withstand pressures which may safely be carried by the drum but to yield and rupture when such pressures are exceeded, permitting the 40 contents of the drum to escape to the atmosphere.

Experience has shown that from some cause heretofore unknown these disks weaken after a comparatively short life averaging only a small number of refillings 45 of the drum and rupture before the danger point is reached, thus releasing the contents of the drum which become a total loss to the owner. A large percentage of gas handled in these drums is lost in this manner. Frequently 50 the disks yield during storage or transportation, sometimes without any apparent immediate cause and under normal conditions, and in other instances under somewhat abnormal conditions such as relatively 55 small increases in temperature which would not endanger the drum or cause the

disk to burst if the latter were in proper condition. I have discovered that the weakening of the disks, which are commonly of bronze, is caused by a weakening of the 60 metal crystals of which the disk is composed, due to "fatigue" caused by flexings of the disk during the filling operation due to the pulsating action of the pump. At 65 each stroke of the pump the disk is momentarily pressed or bulged outward, returning between strokes to substantially a plane condition. This alternate pressure and relief flexes the disk at a circumference adjacent the edge thereof, alternately stressing 70 and relieving the metal fibres and crystals so that the latter are slowly weakened and broken thus reducing the strength of the disk along the line of such circumference. When, therefore, the disk is subjected 75 to any abnormal pressure, even well within that at which it was designed to break, it yields and ruptures with the result referred to above.

My invention is based upon this discovery 80 of the reason for the heretofore mysterious breakage of these safety disks and consists in providing means for so supporting the disk during the filling operation as to relieve it of the stress and strain otherwise 85 imposed upon it by the pulsating action of the filling pump. After the filling is completed the support is removed and the drum is then in the same condition as if my invention had not been applied thereto except 90 that the safety disk retains its original strength.

Referring to the drawing Fig. 1 is a transverse vertical axial section through a drum in condition for filling with my invention 95 applied thereto; Fig. 2 a similar view after the filling is completed and the device embodying my invention removed; Fig. 3 a side elevation of a detail of the preferred form of device embodying my invention, and 100 Figs. 4 and 5 side and end elevations respectively of a detail.

In the drawing I have shown the tube 6 and the filling head 7 thereof as of conventional form, the latter comprising a 105 threaded end 8 screwed into the drum, a nipple 9 for connection to the pump or compressor and a screw valve 10 cooperating with the seat 11 for preventing the escape of gas after the filling is completed. The filling head 7 is as usual further formed with 110 a nipple 12 for the safety device, said nipple

having a passage 13 communicating with the charging passage of the filling head. The nipple 12 is exteriorly threaded and receives an interior threaded union or annulus 14 which has an inwardly projecting annular flange 15 intermediate the threaded portion 16 which screws upon a nipple and a reduced threaded portion 17. In the usual construction to which my invention is applied the safety disk 18 is clamped between the flange 15 and the end of the nipple, a fiber washer 19 packing the joint. A plug 20 is not employed commonly in my device when ready for shipment or storage, to close the outer end of the cap or section, but a passage to the air is provided at 21 which, when the safety disk is ruptured, permits the escape of the gas contained in the drum.

The above description applies equally to 20 the gas drum as commonly employed and to such drum as it is employed in connection with my invention. It will be obvious that with each stroke of the compressor a pulsation of pressure is communicated to the 25 safety disk 18 which is somewhat relieved between strokes so that there is a constant fluctuation or pulsing action of the diaphragm during the charging operation as indicated above, and, as in the device as heretofore constructed the diaphragm must sustain these pulsations unsupported, it ultimately weakens under the intermittent flexure until it is no longer able to withstand the pressure for which it was designed and 30 bursts under a pressure which may be far below that for which the diaphragm was designed.

By my invention I support the diaphragm during the charging operation by a solid 40 abutment so that it is not subjected to flexure by the pulsations of the pump and therefore the fibers and crystals thereof retain their original strength and the life of the disk is almost indefinitely prolonged.

45 Obviously, the specific means for support-

ing the disk may vary widely. My preferred means for the purpose, as illustrated in Figs. 1 and 3, is a screw plug 22 fitting the thread 17 in the safety cap and having an extension 23 of such diameter and length 50 as to extend through the internal flange of the safety cap and bear evenly against the safety disk when the enlarged threaded portion of the plug seats against the flange 15. Preferably, the length of the extension 23 55 is not such as to materially bend or displace the safety disk. For convenience of operation a hand wheel 24 is applied to the outer end of the plug 22. It will now be seen that by removing the plug 20 and replacing it 60 by the charging plug 22 prior to the filling operation the diaphragm is rigidly supported against the pulsations of the pump and therefore its fiber and crystals are not stretched, tensed or weakened during the 65 filling operation. When the filling is completed, the filling plug is removed and the plug 20 substituted therefor, which plug does not support the diaphragm and permits it to yield and rupture under dangerous pressures 70 and permit the gas in the container to escape through the opening 21.

I claim:

1. A gas drum comprising a container proper and a filling head, a nipple on the 75 filling head, a union on the nipple, a safety disc the edge of which is clamped between the nipple and the union, and a plug screwed into the union and engaging the safety disc.

2. A gas drum comprising a container and a filling head, a nipple on the filling head having a passage communicating with the interior of the drum, a safety cap on said nipple having an interior flange, a safety disk intermediate said flange and nipple, 80 said cap being threaded beyond the flange, a threaded plug screwed into the safety cap and having a projection bearing upon the safety disk and means for turning said plug. 85

WILLIAM JAMES TRAXEL.
